United States Patent

Des. 237,651
Patented Nov. 11, 1975

237,651

PLANETARY MICROFILMER OR THE LIKE

Andrew V. McClare, Rochester, N.Y., assignor to
Eastman Kodak Company, Rochester, N.Y.

Filed Aug. 1, 1974, Ser. No. 493,571

Term of patent 14 years

Int. Cl. D16—03

U.S. Cl. D61—1 Q

FIG. 1

FIG. 2

FIG. 3

FIG. 1 is a left front perspective view of a planetary microfilmer or the like showing my new design;

FIG. 2 is a right rear perspective view thereof; and

FIG. 3 is a top plan view thereof.

I claim:

The ornamental design for a planetary microfilmer or the like, as shown.
